Attorney.

UNITED STATES PATENT OFFICE

2,556,007

LUBRICATING ATTACHMENT FOR
KNITTING MACHINES

William R. Slagle, Harriman, Tenn.

Application January 7, 1947, Serial No. 720,518

7 Claims. (Cl. 66—8)

1

This invention relates to knitting machines, and more particularly to those of the cylindrical knitting type wherein there are reciprocating elements such as a cylinder and a stem, the said cylinder being a carrier for knitting elements which reciprocate on the outer surface of the cylinder, this being a well known type of cylindrical knitting assembly.

In machines of this character, there has been difficulty in supplying lubricant to the contiguous surfaces of the cylinder and stem which is desirable in order that the cylinder will work freely in rising and descending, because in machines of this type now in common use, rust forms on the stem and the inner surface of the cylinder, causing impairment of the operation that results in a number of defects in the production, as, for instance, in knitting footwear, the knitting is so imperfect as to cause what is known as "loose foot" and looper waste, and to rectify and restore the parts to effective operative condition, a cam of the machine must be ground or abraded and the cam must then be restored to its normal operative condition so that the looper course is regulated. Another disadvantageous result is that when the rust, to which reference has been made, is removed for the purpose of remedying the defects mentioned, lost motion occurs, due to the loose connection or contact between the cylinder and the stem, allowing them to vibrate with relation to each other and causing wear to other parts of the knitting machine with which the stem and cylinder are associated.

As a further result of the impairment, due to the accumulated rust, the welt develops loose places before the cylinder reaches its lowermost descent, and at other times the cylinder, is arrested before it reaches its lowermost point of travel and causes the leg of the stocking to be elongated.

As a further defect, due to the accumulation of rust, the spline or key which is usually interposed between the cylinder and stem will wear and, if the wear is even slight, the machine would be thrown out of time and will result in breaking needles and they, of course, have to be replaced, so that the foregoing and other results, due to the accumulation of rust, of which those skilled in the art are aware, emphasizes the desirability of effective lubrication which will prevent either the stem or the cylinder from developing accumulations hazardous to the proper operation of the machine. Therefore, an object of this invention is to produce novel means for supplying lubricant to the contiguous sur-

2

faces of a stem and a cylinder of the knitting machine.

A further object of this invention is to provide a holder for an oil supply, preferably adapted to be superimposed on the end of a stem of a knitting machine and having means for transferring oil from the reservoir or oil holder to positions where said oil or lubricant will be deposited in contact with the walls or surfaces of the operating parts, that is to say the stem and cylinder; and it is furthermore the purpose of the inventor to provide the upper end of the stem with clearances or spaces in which the lubricant dispensers may be lodged in such operative relation to the inner surface of the cylinder and the outer surface of the stem that lubricant will find its way between the surfaces and afford efficient lubrication or oiling or greasing of the contacting surfaces.

20 A still further object of the invention is to provide a device of the character which can be applied to installations or knitting machines now in operation without material change in such installations, and the said device is comparatively inexpensive and has proven efficient and satisfactory in use.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which:

Figure 1 illustrates a sectional view of a fragment of a stem and cylinder assembled with a lubricating device embodying the invention applied thereto;

Figure 2 illustrates a horizontal sectional view on the line 2—2 of Fig. 1;

Figure 3 illustrates a view in side elevation of the lubricant tank and parts associated with it;

45 Figure 4 illustrates a top plan view of a fragment of the lubricant holder;

Figure 5 illustrates a vertical sectional view of the lubricant holder;

Figure 6 illustrates a horizontal section on the 50 line 6—6 of Fig. 5 of the lubricant holder or reservoir;

Figure 7 illustrates a sectional view of an assembly of a lubricant holder and stem, the upper end of the stem being modified and provided with holes in which the wicks are lodged; and

Figure 8 illustrates a detail view of a modified means of lubricating the parts.

In these drawings 10 denotes a stem, 11 a cylinder of a cylindrical knitting machine, the said stem having a key or spline (not shown), which projects into a slot 13 in the inner surface of the wall of the cylinder, so that by this means the cylinder and stem are maintained in alinement. The cylinder carries conventional types of knitting instrumentalities 14 which need not, it is thought, be described or illustrated in further detail for an understanding of this part of the invention.

In that embodiment of the invention illustrated in Figure 1, the upper end of the stem has its external surface beveled for a suitable distance, as at 15, to form a clearance in which lubricant distributors 16 are stationed, and these distributors preferably terminate at the junction of the inner wall of the cylinder and the outer surface of the stem, as shown in Fig. 1. The lubricant reservoir has a key or spline 12 movable in the slot 13 of the cylinder to hold it against rotation. The lubricant distributors are preferably in the nature of wicks whose ends are lodged in tubes 17 in the bottom of the lubricant holder or reservoir 19, the top of which reservoir has a filling aperture 29 and a vent hole 21. The inner wall of the lubricant holder or reservoir is elongated to form a skirt 22 which fits within the stem, and preferably the joint between the stem and the cylinder is sufficiently close to result in a frictional engagement which serves to retain the reservoir in place, although it can be removed by lifting it from the end of the stem when new wicks are to be installed, or for other reasons.

The modified form as shown in Figure 7 is modified only to the extent that the upper end of the stem 10 has diagonally disposed holes or ducts 24 which extend from the transverse center, or approximately so, of the top of the stem to the outer edge of the stem, so that in this form, lubricant is distributed in approximately the same fashion as that described in connection with that of the other figures of the drawing.

A still further modified means of distributing the lubricant might be adopted, as shown in Figure 8, wherein the beveled outer surface of the stem may form a lodgment for a lubricant holder or distributor which, in this modified form, preferably comprises a fibrous element formed into a packing or ring 25 lodged in the channel 26 formed by the beveled upper end of the said stem.

It is believed that those skilled in the art will appreciate the many advantages resulting from the prevention of corrosion of the contacting parts of the machine of this character and further résumé of the resultant advantages is believed unnecessary.

I claim:

1. In a cylindrical knitting machine having a coacting cylinder and stem slidably assembled, the upper end of the stem being beveled to form a clearance, a lubricant reservoir on the upper end of the said stem having wicks projecting downwardly through the said clearance for contacting the inner wall of the cylinder and dis-

tributing lubricant between the contacting surfaces of the cylinder and stem.

2. In a cylindrical knitting machine having a coacting cylinder and stem slidably assembled, lubricant reservoir on the upper end of said stem having wicks projecting downwardly through beveled clearances in the upper end of the stem and operative to contact the inner wall of the cylinder and distribute lubricant between the contacting surfaces of the cylinder and stem.

3. In a cylindrical knitting machine having a coacting cylinder and stem slidably assembled, a lubricant reservoir on the upper end of the said stem, a flange extending downwardly and contacting the inner surface of said stem, the said reservoir having lubricant distributing elements extending downwardly through beveled clearances formed on the upper end of the stem and operative to distribute lubricant to the contacting surfaces of the stem and cylinder.

4. In a cylindrical knitting machine having a coacting cylinder and stem slidably assembled, the upper end of the stem being beveled to form a clearance a lubricant reservoir on the upper end of said stem, a lubricant distributing element in the said clearance and communicating with said reservoir and operative to convey lubricant to the contacting surfaces of the stem and cylinder.

5. In a cylindrical knitting machine having a coacting cylinder and stem slidably assembled, said stem having its external surface at its upper end beveled to form a clearance, a lubricant reservoir positioned on the upper end of said stem, and means positioned in said clearance and communicating with said lubricant reservoir for lubricating the contiguous surfaces of the stem and cylinder.

6. In a cylindrical knitting machine having a coacting cylinder and stem slidably assembled, said stem having its external surface at its upper end beveled to form a clearance, a lubricant reservoir positioned on the upper end of said stem and having openings in the bottom thereof communicating with said beveled clearance for permitting lubricant from said reservoir to pass through said clearance to the contiguous surfaces of the stem and cylinder.

7. In a cylindrical knitting machine having a coacting cylinder and a stem slidably assembled, a clearance formed at the upper end of the stem, a lubricant reservoir on the upper end of said stem, and means positioned at said clearance and communicating with said lubricant reservoir for transferring lubricant from the reservoir to the contiguous surfaces of the stem and cylinder.
